WAISTBAND CONSTRUCTION

Paul E. Fenton, Middlebury, Conn., assignor to
 Scovill Manufacturing Company, Waterbury,
 Conn., a corporation of Connecticut

Application December 3, 1945, Serial No. 632,426

1 Claim. (Cl. 2—237)

1

This invention relates to a garment construction and specifically to any garment having an elasticized waist band throughout its entire length.

The object of this invention is in the construction of any garment having a completely elasticized waist band and involves the feature of having the elasticized waist band interrupted or cut through with a slot extending down into the garment proper and brought together in an overlapping manner and releasably held together with fastener elements and giving preference to snap fastener elements. This is to allow the garment to have its waist band open up beyond its normal size with all the attendant advantages of any garment having an open type waist band for purposes of dressing into the same and furthermore prevents subjecting the elastic material in the waist band to any excessive strains.

A further object of this invention is to provide a garment having an elasticized waist band of the above character and wherein a full-length fly front is provided in the front of the garment extending through the waist band and adapted to be detachably secured together as by fastener elements and is of particular use in men's shorts.

In the accompanying drawing:

Fig. 1 shows a perspective view of a pair of shorts embodying the invention and showing the full-length fly front in closed position and secured together as by snap fastener elements, and

Fig. 2 is a similar view, but showing the outer flap of the fly front partially opened to show better the complementary fastener elements.

In garments of this character heretofore wherein a completely elasticized waist band has been employed they have been generally of two forms. One form consists of having a strip of elastic webbing attached to the inside of the waist band throughout its entire length as by stitching, and having the cloth of the garment in the waist band area gather into folds in what is known as a Shirred construction. Such is the type of construction shown in the accompanying drawing. The other known form is to employ a hem for the waist band where the latter is also of the Shirred construction and running an endless elastic webbing through the entire hem. These types of garments have been generally known as the "Boxer" shorts and the same type of waist band construction may be found in women's and children's wearing apparel. One of the faults of these types of garments has been that the waist band has to be stretched considerably in pulling the garment up over the hips of the wearer and

2

affording only a relatively small opening into the garment when getting dressed with the same. Also in the "Boxer" type of shorts the fly front opening is of a limited length in view of the fact that a considerable length of the fly front has been stitched down adjacent the waist band so as not to extend through the completely elasticized waist band. To overcome these faults it is the purpose of my invention to cut through the completely elasticized waist band to afford all the advantages of the standard garments with full-length fly fronts, and at the same time to retain the advantages of a completely elasticized waist band by the application of fastener elements to the overlapping fly front.

Referring now to the drawing in which like reference numerals designate like parts, the numeral 10 indicates generally a pair of shorts wherein the upper waist band 11 has the cloth material thereof gathered together in folds as at 12 with an elastic webbing 13 stitched to the inside of said waist band 11 throughout its entire length as by upper and lower stitchings 14 and 14a respectively. The more complete construction of the full-length fly front opening is best shown in Fig. 2 wherein the under fly flap 15 has the cloth folded inwardly upon itself for the full-length of the fly front as determined by the bar stitching 16 adjacent the crotch 17 and vertically stitched as at 18. Also it is to be noted that this folded fly front encloses the end of the elastic webbing 13 as at 19 and is permanently anchored there in place as by stitchings 14, 14a and 18. A pair of stud members 20 is attached 30 to the front face of the under flap 15, one being positioned in the folded end portion 19 of the waist band proper while the other one is disposed some distance therebelow.

The upper or front fly flap 21 is constructed 40 similarly to the under flap 15 wherein the cloth is likewise folded inwardly upon itself for the full-length of the fly front 21 and stitched in place as by vertical stitching 22, and also enfolding the opposite end of the elastic webbing as at 23 and similarly anchored in place by stitchings 14, 14a and 22. Attached to the underside of the front fly flap 21 are socket elements 24 complementary to the studs 20 on the under flap 15, and said socket elements are held in position 50 by any of the usual forms of fastener devices 25 as shown in Fig. 1 and extending through the material of the front flap 21 for anchoring the socket in place.

While I have shown only two fastener elements 55 attached to the fly front, it is to be understood

that more may be attached if desired, and also two might be placed upon the adjacent ends of the waist band itself.

While this invention has been shown in conjunction with shorts, it should be understood that it is applicable to various types of garments in men's, women's and children's wearing apparel wherein it is desired to have a completely elasticized waist band with the advantages of being opened beyond the normal size and brought together with detachable snap fastener elements.

I claim:

In a nether garment having a waist band, elastic webbing attached to the inner surface of said waist band throughout its entire length by a line of stitching adjacent the upper and lower edges of said webbing, the cloth of said waist band portion of said garment being stitched to said webbing in a shirred effect, a full-length overlapping fly front opening through said waist band, both portions of said overlapping fly front being folded inwardly upon themselves for the full length of said fly front and stitched there in place with the upper folded portions enclosing the opposite ends of the elastic webbing, the latter

extending substantially the full depth of said folded portions, and complementary snap fastener elements attached to the ends of the waist band through the folded portion of said fly front and the enclosed end portions of said webbing, the enclosed webbing in said folded portions of said fly front serving to reinforce that portion of the waist band to which said elements are attached.
